HARVEY HUBBELL, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

ELECTRIC SOCKET-SWITCH.

No. 892,375.

Specification of Letters Patent. Patented June 30, 1908.

Application filed June 7, 1907. Serial No. 377,764.

To all whom it may concern:

Be it known that I, HARVEY HUBBELL, a citizen of the United States, residing at Bridgeport, county of Fairfield, State of Connecticut, have invented a new and useful Electric Socket-Switch, of which the following is a specification.

This invention relates to electric socket switches and has for its object to simplify and cheapen their construction and to greatly improve their operation in use.

With these ends in view I have devised the simple and novel electric socket switch of which the following description in connection with the accompanying drawings is a specification, reference characters being used to indicate the several parts.

Figure 1 is an elevation of my novel switch detached from the socket shell, the contact bar being in position to close the circuit; Fig. 2 a vertical section on the line 2—2 in Fig. 1, a lamp being in engagement with the screw shell; Fig. 3 a transverse section on the line 3—3 in Fig. 2 looking down; Fig. 4 an inverted plan view of the contact bar detached showing the rollers in place therein; Fig. 5 a view of the contact plate detached; Fig. 6 an inverted sectional view similar to Fig. 3 illustrating a variant form of construction; Fig. 7 a detail view corresponding with Fig. 6 showing the contact plate from a point of view at right angles to the point of view in Fig. 6, the contact bar having been given a quarter turn; Fig. 8 a detail sectional view illustrating a third form of the invention; Fig. 9 an inverted sectional view illustrating a fourth form of the invention; Fig. 10 an elevation of the shaft detached; and Fig. 11 is a face view of the contact bar corresponding with Figs. 6 and 7.

10 and 11 denote the parts of a block of insulating material which in the assembled position lies within the socket shell (not shown).

45 12 denotes the contact plate as a whole. This contact plate comprises an attaching plate 13 which is secured to one of the parts of the block by means of a screw 14, a plate 15 lying at right angles to the attaching plate 50 and carrying a binding screw 16 which also engages one of the parts of the block and a plate 17 lying at right angles to the attaching plate and parallel with plate 15, said plate 17 being provided with a plurality of projections, in the present instance four, indicated

by 18 and between the projections with rounded depressions indicated by 19. 20 denotes the other binding screw which passes through a spring contact plate 22 and engages one of the parts of the block. The 60 free end of spring contact plate 22 extends inward into position to be engaged by the hub 23 of an incandescent lamp base, indicated by 24.

25 indicates the screw shell which receives 65 the lamp base and is secured to the block by screws 26 (see Figs. 3, 6 and 9 and dotted lines in Fig. 1). These screws also secure the parts of the block together.

It will, of course, be understood that the 70 parts of the block are provided with suitable recesses to receive the parts of the switch. These recesses are not, however, indicated specifically by numbers, as their shape and arrangement may be varied greatly without 75 affecting the principle of the invention.

27 denotes the shaft which is mounted to rotate in either direction and also, in the first, second and third forms, to move longitudinally in plates 15 and 17. The shaft is 80 provided with a key 28 which is molded thereon or otherwise rigidly secured thereto and with pairs of lugs indicated respectively by 29 and 30.

31 denotes the contact bar which is provided with a hole 32 to receive the shaft and with slots 33 extending diametrically from the hole which receive loosely lugs 30 on the shaft so as to permit forward movement of the contact bar independently of the shaft. 90 The shaft is provided with a collar 53, outside lugs 30, which bears on the outer face of the contact bar. The contact bar is provided with contact arms 34 for a purpose presently to be described. The contact bar 95 is preferably, but not necessarily, provided with rollers which engage the projections and recesses on the contact plate. In the first form the contact bar is provided with sockets 35 which receive loosely rollers 36, said 100 rollers being adapted to ride up projections 18 on plate 17 when the shaft is rotated in either direction and then having passed the projections to drop downward into the depressions. The slots 33 in the contact bar 105 receive the lugs 30 on the shaft loosely enough to permit forward movement of the contact bar independently of the shaft when the rollers have been caused to ride up the projections and past the apexes thereof. 110

The forward and inward movement of the shaft and contact bar and the instant dropping of the rollers into the depressions, causing the switch to operate with a snap, is produced by a spring 37 encircling the shaft and the ends of which bear respectively against plate 17 and a washer 38 on the shaft which in turn bears upon lugs 29. The lugs 29 upon the shaft engage plate 15 of the contact plate and limit the inward movement of the shaft.

39 denotes a spring contact plate which is adapted to be engaged by contact arms 34 and is secured in place between the screw shell and the block by one of the screws 26 or in any suitable manner.

The passage of the current is as follows: From binding screw 16 to contact plate 12 and through the rollers to the contact bar 20 and contact arms, from the contact arms to spring contact plate 39, the screw shell and the lamp base; from the lamp it passes by means of hub 23 and spring contact plate 22 to binding screw 20. Figs. 1 and 2 show the 25 position of the parts when the circuit is closed. To open the circuit, the shaft is given a quarter turn in either direction. This causes the rollers to ride up the projections and having passed them the spring will 30 force the shaft and contact bar inward again and the rollers will drop into the depressions forward of the projections just passed. This will place the contact bar and the contact arms in a position at right angles to the position 35 shown in Figs. 1 and 2 in which neither of the contact arms will be in engagement with spring contact plate 39. A quarter turn of the shaft from this position either forward or backward will place the contact bar 40 and contact arm in the position shown in Figs. 1 and 2 in which one of the contact arms is in engagement with spring contact plate 39.

In the form illustrated in Figs. 6, 7 and 11, 45 the structure differs in that the projections 18 and depressions 19 are on the contact bar instead of on the contact plate and face inward instead of outward and the rollers are carried by the contact plate. In this form 50 contact plate 12 comprises an attaching plate 13, a plate 15 at right angles thereto in which is a binding screw 16 which engages one of the parts of the block as before. At the outer end of the contact plate is a head 40 in 55 which rollers 41 are journaled. The spring 37 bears against a washer 38 as before and against a washer 55 which in turn engages the head. 42 denotes the contact bar which is provided with contact arms 34 and with 60 projections 18 and depressions 19 which are engaged by the rollers in the same manner as in the other form except that the parts are reversed. The operation in use is precisely the same as in the other form.

The form illustrated in Fig. 8 differs from

the first form only in that the rollers which are indicated by 43 are provided with trunnions 44 which are socketed in the contact bar. Aside from this change the operation is precisely the same as in the other form.

In the form illustrated in Fig. 9, the contact plate and contact bar are located in a recess in the block and at the inner end of the shaft. In this form the contact plate 12 comprises an attaching plate 13, and a plate 45 through which the shaft passes and which is provided with projections 18 and depressions 19. 46 denotes the contact bar which is provided with transverse slots 47 which are engaged by the ends of a pin 48 which project from shaft 27. The rollers 49 are journaled in the contact bar and engage the projections and depressions as in the other forms. In this form, the shaft has no longitudinal or endwise movement but rotary movement only, the end of the shaft being flattened or otherwise enlarged, as at 54, to retain it against other than rotary movement by engagement with plate 45. At the outer end of the contact plate is a plate 50 at 9 right angles to the attaching plate through which the shaft passes and which is provided with an arm 51 which carries a binding screw 52. The spring 37 in this form bears against plate 50 and against the back of the contact bar. The contact bar is loosely engaged by the lugs 30 upon the shaft the same as in the other forms, this engagement not being shown in the drawings. When the shaft is rotated, the contact bar is carried thereby and the rollers ride up projections against the power of the spring the same as in the other forms, the contact bar sliding longitudinally on the shaft as is permitted by the pin and slot engagement. When the 10 rollers pass the tops of the projections, the spring will force the contact bar inward instantly and cause the rollers to engage the depressions as in the other forms. The 11 passage of the current is the same as in the 12 other forms.

Having thus described my invention, I claim:

1. A socket switch comprising a contact bar and a contact plate, one of said parts being provided with alternate projections and depressions and the other part engaging said projections and depressions, a shaft loosely engaging the contact bar for the purpose set forth, and means for holding the contact bar and contact plate in engagement.

2. A socket switch comprising a contact bar and a contact plate, one of said parts being provided with alternate projections and depressions and the other part with rollers adapted to engage said projections and depressions, a shaft loosely engaging the contact bar and means for holding the rollers closely in engagement with the corresponding parts.

3. A socket switch comprising a contact bar having a hole and slots extending therefrom and a contact plate, one of said parts being provided with alternate projections and 5 depressions and the other part engaging said projections and depressions, a shaft passing through the hole in the contact bar and having lugs loosely engaging the slots for the purpose set forth, and a spring surrounding 10 the shaft and acting to retain the contact bar and contact plate in engagement.

4. A socket switch comprising a contact bar having sockets and rollers in said sockets and a contact plate provided with alternate 15 projections and depressions, a shaft loosely engaging the contact bar and means for retaining the rollers closely in engagement with the projections and depressions.

5. A socket switch comprising a contact 20 plate consisting of plates 13, 15 and 17, said plate 17 being provided with alternate projections and depressions, a contact bar carrying rollers engaging the projections and depressions, a shaft mounted to rotate in plates 15 and 17 and means for loosely connecting the shaft and the contact bar.

6. A socket switch comprising a contact 25 plate consisting of an attaching plate 13 and plates 15 and 17 at right angles thereto, said plate 17 being provided with alternate projections and depressions, a contact bar carrying rollers engaging the projections and depressions, a shaft mounted to rotate in plates 15 and 17, means for loosely connecting 30 the shaft and the contact bar and means for retaining the rollers closely in engagement with the projections and depressions, so that when the shaft is rotated in either direction the rollers will be forced up the projections and having passed the projections 35 will be instantly forced into the depressions, substantially as described, for the purpose specified.

7. A socket switch comprising an insulating block, a screw shell secured thereto, a spring contact plate 39 in engagement with the screw shell, a spring contact plate 22 carrying a binding screw and adapted to be engaged by the hub of a lamp, a contact 45 plate 12 carrying a binding screw, a contact bar, said contact plate and contact bar being provided respectively with projections and depressions and with rollers engaging said projections and depressions and said contact bar being provided with contact arms 50 adapted to engage spring contact plate 39, a shaft loosely engaging the contact bar and mounted to rotate in the contact plate and means for retaining the contact bar and contact 55 plate in engagement.

8. In a socket switch the combination 60 with an insulating block, a screw shell, a contact plate having alternate projections and depressions and a contact bar adapted to engage said projections and depressions and

having contact arms, of a shaft mounted to rotate in the contact plate and loosely engaging the contact bar for the purpose set forth, a spring contact plate adapted to be engaged by the hub of a lamp and a spring 70 contact plate engaged by the screw shell and adapted to be engaged by the contact arms.

9. A socket switch comprising a contact bar and a contact plate, one of said parts being provided with alternate projections and 75 depressions and the other part engaging said projections and depressions, a shaft loosely engaging the contact bar for the purpose set forth and having a collar bearing on the outer face of said bar, and a spring acting to 80 draw the shaft and contact bar inward and retain the contact bar and contact plate in engagement.

10. A socket switch comprising a contact bar and a contact plate, one of said parts being provided with alternate projections and 85 depressions and the other part with rollers adapted to engage said projections and depressions, a shaft loosely engaging the contact bar and having a collar bearing on the outer face of said bar and a spring for retaining the rollers in engagement with the 90 projections and depressions.

11. A socket switch comprising a contact bar and a contact plate, one of said parts being provided with projections and intermediate said projections with rounded depressions, and the other part being provided with rollers adapted to engage said projections and depressions, a shaft free to rotate 95 in either direction and loosely engaging the contact bar and a spring for retaining the rollers in engagement with the projections and depressions.

12. A socket switch comprising a contact bar and a contact plate, one of said parts being provided with four projections and intermediate said projections with rounded 100 depressions and the other part being provided with rollers adapted to engage said projections and depressions, a shaft free to rotate in either direction and loosely engaging the contact bar and means for retaining the rollers in engagement with the 105 projections and depressions.

13. A socket switch comprising a contact bar and a contact plate, one of said parts being provided with four projections and intermediate said projections with rounded 110 depressions and the other part being provided with rollers adapted to engage said projections and depressions, a shaft free to rotate in either direction and to move longitudinally, said shaft loosely engaging the contact bar and having a collar bearing on the outer face of said bar and a spring acting to 115 draw the shaft and contact bar inward, substantially as described, for the purpose specified.

14. A socket switch comprising a contact 120

bar provided with rollers, a contact plate provided with projections, and intermediate said projections with rounded depressions, a shaft free to rotate in either direction and 5 loosely engaging the contact bar and means for retaining the rollers in engagement with the projections and depressions.

15. A socket switch comprising a contact bar provided with sockets and rollers in said 10 sockets, a contact plate provided with projections and intermediate said projections with rounded depressions, a shaft free to rotate in either direction and to move longi-

tudinally, said shaft loosely engaging the contact bar and having a collar bearing on 15 the outer face of said bar and a spring for drawing the shaft and contact bar inward and causing the rollers to engage depressions instantly when the contact bar is moved in either direction past projections. 20

In testimony whereof I affix my signature, in presence of two witnesses.

HARVEY HUBBELL.
